UNITED STATES PATENT OFFICE.

FRANCIS K. ADAMS, OF NASHOTAH, WISCONSIN.

CAR-COUPING.

SPECIFICATION forming part of Letters Patent No. 295,609, dated March 25, 1884.

Application filed September 18, 1882. (No model.)

To all whom it may concern:

Be it known that I, FRANCIS K. ADAMS, a citizen of the United States, residing at Nashotah, in the county of Waukesha and State of Wisconsin, have invented certain new and useful Improvements in Car-Couplings; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in car-coupling.

The object of my invention is to provide a coupling which will retain the link in a true horizontal position preparatory to entering the 20 draw-bar of an approaching car, and which, as it enters the car, will be automatically coupled thereto.

The construction and operation of my invention are further explained by reference to 25 the accompanying drawings, in which—

Figure 1 represents a view of the draw-bar, in part perspective and in part a longitudinal vertical section. Fig. 2 is a longitudinal vertical section. Fig. 3 is a top view, and 30 Fig. 4 is a perspective of the latch.

Like parts are represented by the same reference-letter throughout the several views.

A is the draw-bar. B is the coupling-link. C is a latch. The latch C is adapted to be 35 thrown upward by contact with the link as it enters the draw-bar, and to drop of its own gravity as the end of the link passes beneath it, when the point E of the latch passes through the link, and thus retains the 40 link substantially as an ordinary pin.

D is a recess formed in the draw-bar for the reception of the latch. Both the front end of the latch a and front wall of said recess b incline slightly forward and downward, 45 whereby a downward tendency is given to said latch as it is drawn forward against said inclined surface, and is thereby prevented from working upward or bounding out of the link as the train is being drawn. The 50 front end of said latch between a and the point E is curved so as to present a rounded surface to the link as it enters the draw-bar,

whereby it is thrown upward by the forward movement of the link as it enters. The latch C is provided with lugs F F, which project 55 horizontally from each side thereof and engage in the recesses G G, whereby the rear end of said latch is retained in place.

H is a recess for the reception of the link B. Its upper and lower walls are formed on 60 a true horizontal plane parallel to each other, whereby the link is retained in a nearly horizontal position, and its front end adapted to enter the draw-bar of an approaching car, as mentioned. The recess G extends downward 65 and rearward, so that the latch C may be moved rearward by the link before raising, whereby the angular point at d will escape contact with the front wall of the recess b as it rises. The point E of the latch, when drawn 70 forward, rests in the angular recess I, and as said latch is first brought in contact with the link and moved backward it is slightly raised by contact of the point E with the surface of said recess as it moves backward over it when 75 the upward movement of the latch is completed by the action of the link as it is forced beneath it. The front end of the latch is provided with a ring, J, for the reception of a cord or chain, by which it may be raised from 80 the top of a car when desirous to uncouple the device.

Having thus described my invention, what I 85 claim as new, and desire to secure by Letters Patent, is—

In a car-coupling, the draw-bar A, provided with horizontal recess H, angular recess I, vertical slot D, and recesses G G, in combination with the latch C, provided with lugs F F, adapted to operate in said recesses G G, said 90 latch C being adapted to be thrown upward by contact with said angular recess I as it is moved rearward by the approaching link preparatory to the link entering beneath it, said horizontal recess H being adapted to hold said 95 link in position to enter an approaching draw-bar or coupling, substantially as and for the purpose specified.

In testimony whereof I affix my signature in presence of two witnesses.

FRANCIS K. ADAMS.
